L. W. Hayden,

Crimping Leather.

No 31664.

Patented Mar 12, 1861.

In witness,
John C. M. Alexander
Arthur Yeatman
T. H. Alexander

Inventor
L. W. Hayden

UNITED STATES PATENT OFFICE.

LEVI W. HAYDEN, OF WILKES-BARRE, PENNSYLVANIA.

MACHINE FOR CRIMPING BOOTS.

Specification of Letters Patent No. 31,664, dated March 12, 1861.

To all whom it may concern:

Be it known that I, LEVI W. HAYDEN, of Wilkes-Barre, in the county of Luzerne and State of Pennsylvania, have invented certain new and useful Improvements in Boot-Crimping Machines; and I do hereby declare that the following is a full, clear, and exact description of the same, reference being had to the accompanying drawings and to the letters of reference marked thereon.

The nature of my invention consists in constructing and arranging the several parts of this machine in the manner hereinafter set forth.

15 In the annexed drawings Figures 1 and 3 represent side elevations. Fig. 2 is a view of a part which will be described.

In the figures A represents the stand or body of the machine. Upon and to this stand are secured and hinged two bars or arms D, D, the upper ends of said bars being formed to correspond with the shape of the form of the crimp, the insides of said ends being made flat so as to fit snugly 25 against the form F'. The lower ends of the bars D D are hinged as shown at x, x, to the stand or frame.

G represents a rack bar which is so constructed upon its top F as to receive the 30 form F'. The top is provided with a groove in which the form rests. A variety of forms may be used upon the top F, any size being used at the will of the operator. L represents a pinion which gears into the rack 35 upon the lower portion of the bar G, and which serves to operate said bar. The pinion L is secured upon a shaft which lies across the stand A. Upon the shaft of this pinion is secured a ratchet wheel H. I represents a lever connected loosely to the shaft 40 just spoken of and which has attached to it a pawl J, which catches into the teeth upon the ratchet wheel H, as seen in Fig. 1. The lever I and pawl J serve to move the ratchet 45 wheel H in one direction while the ratchet or pawl c, secured to the frame or stand A, serves to station the said wheel H at any desired position.

a, a, represent clamps which are con-

nected to a treadle e, by means of the straps 50 d, d. These clamps consist of two jaws pivoted together and regulated by means of set screws h, h. When the leather to be crimped is placed upon the form F', the clamps a, a, 55 catch it upon each side, and draw, and secure it down to the form.

P represents a plate with ratchet teeth which teeth serve to catch the treadle and hold it down when desirable.

E represents a clamp consisting of a bar 60 with two arms which embrace the bars D, D, being pivoted to one of said bars at i.

N represents a set screw which passes into the end of the bar E and presses against a chuck R which intervenes between it and the 65 bar D. When the screw N presses against the chuck R it draws the two bars D, D, together and causes them to press at their upper ends against the leather upon the form. When the screw N is loosened the 70 chuck R may be raised and then the two arms or bars D, D, may be opened.

In using this machine the leather to be crimped is placed upon the form F'. The clamps a, a, then take hold upon it on each 75 side and draw it down tight upon the form by the use of the treadle. The treadle is then secured down by the teeth on plate P. The bars D, D, are then brought up against the leather upon each side of the form and 80 are pressed against it by means of the screw N. The leather is allowed to remain in this position as long as desirable. A tack or two may then secure it to the form and it may be removed to make room for another. 85

Having thus fully described my invention what I claim as new and desire to secure by Letters Patent is—

The employment of the rack bar G and the bars D, D, as constructed, the clamps 90 a, a, the straps d, d, the treadle e, clamp E, chuck R and set screw N, arranged and connected to form a machine for crimping leather substantially as specified.

LEVI W. HAYDEN.
